UNITED STATES PATENT OFFICE.

WILLIAM H. DAY, OF EAST HAVEN, CONNECTICUT, ASSIGNOR TO INDEX VISIBLE, INC.,
OF NEW HAVEN, CONNECTICUT.

INDEX OR FILE LEAF.

Application filed June 29, 1921. Serial No. 481,363.

To all whom it may concern:

Be it known that I, WILLIAM H. DAY, a citizen of the United States, residing in East Haven, county of New Haven, State of Connecticut, have invented certain new and useful Improvements in Index or File Leaves, of which the following is a full, clear, and exact description.

This invention relates to indexes, files or indicators of that type in which a holder or carrier is employed to receive and mount a relatively long strip of paper or the like containing reference material, or if desired, a plurality of cards containing such material.

15 The carrier or holder is usually provided with some sort of guides or retaining means by which the reference bearing members are held in operative position, and these carriers may be either swingingly mounted upon a frame to be manipulated after the manner of the leaves of a book, as shown in the patent to R. D. Hayes, No. 1,223,168, granted April 17, 1917, or may be made in the form of shallow drawers adapted to be inserted 25 in a filing cabinet.

It is necessary to move the cards or strips of paper containing the reference material about in the holder to some extent and such movement is, of course, necessary when they 30 are inserted into and removed from the holder. It is, therefore, desirable to so make the holders or carriers that the strips of paper will slide freely within the guides and so that there will be no tendency for these 35 strips or cards to catch or stick. Heretofore, the guides for retaining the reference strips have been formed by connecting to the carrier base separate strips which are provided with flanges spaced from the base to the carrier, in such a manner that the joints between these separate pieces and the carrier base lie adjacent the edges of the reference strips. This often results in the edge of the strip entering into the crevice or crack of 40 this joint between the two members and becoming wedged therein so that free movement of the strip is prevented.

One object of my invention is to overcome the disadvantages above referred to and to 45 provide a carrier with suitable retaining guides so formed that the joint between these guides and the carrier proper will lie below the body of the reference strip and not in such a position that it will interfere 55 with the movement thereof.

Another object of this invention is the provision of a suitable carrier for reference strips which shall be provided with substantially seamless guide channels, so that the danger of a card or strip entering and wedging itself in a seam will be obviated.

A still further object of my invention is the provision of a carrier of the type described which shall be provided with a novel frame upon which the holders of the reference strips are mounted.

To these and other ends the invention consists in the novel features and combinations of parts to be hereinafter described and claimed.

In the accompanying drawings:

Fig. 1 is a front elevation of an index or directory embodying my improvements showing the carriers hinged to swing in the manner of leaves;

Fig. 2 is a top plan view of the device shown in Fig. 1;

Fig. 3 is a side elevation of one of the carriers or leaves mounted upon its support;

Fig. 4 is a sectional view on line 4-4 of 80 Fig. 3;

Fig. 5 is a sectional view on line 5-5 of Fig. 3;

Fig. 6 is a view similar to Fig. 3, but showing a modified form of carrier or leaf;

Fig. 7 is a sectional view on line 7-7 of Fig. 6; and

Fig. 8 is a sectional view similar to that shown in Fig. 7, but showing a still further modification of my invention.

To illustrate the principles of my invention, I have shown an index or directory in which the carriers are mounted as swinging leaves similar to those shown in the patent to R. D. Hayes, above referred to. It will 95 be understood that my improvements may also be applied to carriers which are supported or suspended in other ways.

In the form of my invention shown in Figs. 1 to 5, I have shown at 10 a suitable support provided with guides 11 at the top and bottom thereof, respectively, in which the carriers or leaves 12 are slidably and swingably mounted. The leaves may, when mounted in this manner, be swung open in 100 any desired point, as shown, and when they are thus open, the reference material on one side of the carriers thus exposed will be visible. The leaves 12 comprise a framework formed by the wires or rods 13 and 14.

As shown, the wire 14 is so shaped as to form the front and top and bottom of the frame and the upper and lower portions thereof are extended as arms 15 to mount the carrier 5 in the guides 11. At the ends of these arms are mounted spherical projections 16 to engage in the channels formed in the guides. The material of which these arms are made is sufficiently resilient so that they may be 10 sprung into place and also may be removed at will. The portion 13 of the frame is shaped to form the rear side edge thereof and also to overlap the member 14 at the top and bottom of the leaf and the ends of the 15 member 13 may be soldered at the points 17 and 18 to the rod 14 to secure the parts of the frame rigidly together.

While the details of the structure of the carrier or leaf may be varied to some extent, I have chosen to mount a base plate or base strip 19 upon the frame formed by the rods 13 and 14. This plate may be a thin flat piece of metal and have its ends turned over the rods forming the frame at 25 the four sides thereof, as shown at 20. Upon the carrier formed by the frame and the base strip just described are provided a plurality of channel guides to retain the strips or cards designed to bear the reference material. These retaining channels are formed in the embodiment of my invention which is now being described by the provision of a card-holder 21 having a flat base portion secured flatwise upon the base plate 30 19 and having its side edges turned over above the marginal portions of the base plate at 22 and 23 to provide the retaining 35 flanges. As shown, the holders 21 are thus formed of one piece of material and are secured to the base plates by rivets 24 which lie beneath the strips bearing the reference material. Such a strip is shown at 25 in Fig. 3 operatively mounted in the holder and suitably guided in its movements by the 40 45 flanges 22 and 23.

When the flanges are turned up at the edges of the holder in this way, it is apparent that any sharp angles or corners are obviated, as it may be given a rounded 50 shape and thus the edge of the reference strip is not likely to stick or bind when the strip is moved. Moreover, there is no joint between the flange and the base plate wherein the reference strip may become wedged.

55 The lower edges of the holders 21 may be turned over at 26 to provide a lower retaining flange or support to prevent the reference strips from falling from the holders. As shown in Fig. 3, a plurality of these holders 21 may be mounted upon each side of the carrier or leaf, those on one side thereof being directly opposite the corresponding holders on the opposite side so that the rivets 24 60 65 may pass through the holders on both sides of the carrier to secure them to the latter.

In Figs. 6 and 7, I have shown a somewhat modified form of my invention wherein the frame of the carrier is formed in a different way and a novel means of hinging the carrier to its support is employed. In 70 this form the frame is composed of a single rod or wire 30, which, as shown, is shaped to form the rear edge and the upper and lower sides of the frame, the rod being returned upon itself at the upper and lower 75 edges and extended to form the spring arms 31, which are provided with the hooks 32 adapted to engage the supports 33 in a suitable manner, so that the leaves will be rigidly connected to these supports. The base 80 plate 19 mounted upon this frame is similar in all respects to that described in connection with Figs. 1 to 5, except that the front portion of the same is flanged or hemmed at 85 34 to provide additional strength at this edge in view of the fact that the edge is not protected by a part of the rod 30. The holders 21 are mounted upon the base plate in the same manner, as described in connection with 90 Figs. 1 to 5, and are formed in substantially 95 the same way.

In Fig. 8 I have shown a modified form of my invention wherein the retaining flanges are formed by securing relatively narrow strips upon the base plate 19 instead of 100 holders 21 which extend throughout the width of the reference strips 25. These retaining strips 35 are brought over and secured to the base plate by the rivets 36 at a point which will lie below the reference 105 strips 25, so that even in this form there will be no joint in position to obstruct the edges of the strips. The flanges are then formed by the edges of the members 35 being turned over in a manner similar to 110 the edges of the holders 21. In case of the intermediate flanges formed upon the plate 19, these, if desired, may be formed by a strip of material 37 riveted to the base plate at 38, carried out in either direction from the rivet 38 to extend beneath the reference strips 25, then returned over itself to a point adjacent the rivets 38 where the edges are flanged at 39 115 in the usual manner. It will be apparent that considerable saving of material is achieved in this form, as the material forming the flanges is not continued entirely across the base strip as in the forms of my invention shown in the other figures of the drawing. The advantages, however, of the forms of the other figures in that a rounded flange is provided and one wherein there is no seam to come in conflict with the edge of the reference strip, are retained.

120 While I have shown and described some-
what preferred embodiments of my invention, it is to be understood that the same is not to be limited thereto in all of its details, but is capable of many modifications and 125 130

variations which lie within the spirit of the invention and within the scope of the appended claims.

What I claim is:

- 5 1. In an index or file, a leaf having a surrounding framework of rods, a base plate bent over and secured to said framework and substantially filling the space therein, and an opposed channelled card holder 45
10 cured to each face of the leaf, said card holder comprising a continuous flat strip of material with its lateral edges bent back over the body portion to form opposed card retaining channels.
  - 15 2. In an index or file, a carrier leaf having a base plate and a plurality of carrier strips mounted thereon, each of said carrier strips having a body portion secured flatwise upon the base strip and having edge portions returned over the body portion to provide opposed retaining flanges, said carrier strips being mounted directly opposite each other, back to back, on opposite sides of the carrier leaf and securing means passing through the leaf and the strips on both sides thereof. 60
  - 25 3. In an index or file, a carrier leaf comprising a frame of rods or wire and a base plate mounted therein, said frame being composed of two rods, each bent to form three sides of the frame and overlapping the other rod upon two sides thereof. 65
  - 30 4. In an index or file, a carrier leaf frame having spring arms by which it is supported, said arms being continued to form the top, bottom and one side of the frame, and a rod secured to said arms and forming the other side of the frame. 70
  - 35 5. In an index or file, a carrier frame of two rods, the ends of one rod being se- 75
  - 40
- cured to intermediate portions of the other, and the ends of the second rod being extended to be secured to a support.
6. In an index or file, a carrier or leaf having carrier strips mounted thereon, each of said strips having a flat body portion and both side edge portions returned over the body portion to provide retaining flanges and also having an end edge turned up to provide a supporting flange. 45
  7. A leaf index for holding cards or the like, comprising a base plate, a supporting framework surrounding and secured to said base plate, and a seamless one piece card holder attached to said base plate, said card holder having single bends upon its lateral edges whereby a portion is turned inward from each of said edges toward the median line of said holder to form card retaining flanges. 55
  8. In an index or file, a carrier leaf comprising a framework composed of two rods each bent to form three sides of the frame, a base plate secured to the rods connecting the opposite sides of the frame together, and channeled card holding strips upon said base plate. 60
  9. In an index or file, a carrier leaf comprising a rod bent to form three sides of a rectangular frame, a base plate connecting the three sides thus formed together, and reinforcing strips upon said base plate, said reinforcing strips being seamless pieces of material applied flatwise to said plate and having their lengthwise edges bent inward to form retaining flanges of single thickness for cards or the like. 70

In witness whereof, I have hereunto set my hand this 27th day of June, 1921.

WILLIAM H. DAY.
